UNITED STATES PATENT OFFICE.

CHARLES B. SHEPHERD, OF NEW YORK, N. Y., ASSIGNOR TO WILLARD REID, OF SCARSDALE, NEW YORK.

RAIL ANCHOR.

Application filed March 17, 1928. Serial No. 262,360.

This invention relates to those devices designed and adapted to prevent the longitudinal creep of rails and known as rail anchors.

This invention has for an object the production of a rail anchor which is easy and economical to manufacture and which will produce most satisfactory results in use.

It has for an object the production of a rail anchor having a triple pressure-bearing 10 clamping means.

A further object of this invention is to produce a rail anchor having a clamping means comprising a jaw having two substantially rigid pressure-bearing members or jaws and a 15 yielding resilient pressure-bearing member cooperating with said rigid members.

Further objects will appear from the following description, appended claims and the accompanying drawings forming a part of 20 this specification and in which:

Figure 1 is an isometric view of my rail anchor.

Figure 2 shows my rail anchor applied to a rail base flange, the rail being shown in 25 section.

Figure 3 shows the relation of the parts of the rail anchor to the rail base flange.

Figure 4 shows one of the positions assumed by the rail anchor during its application 30 to the rail base flange.

Figure 5 shows the anchor prior to application (in full lines) and the position of the parts of the anchor after application (in dotted lines).

Referring to the drawings in which like 35 reference numerals designate like parts, there is disclosed a rail anchor having a body member 1. Disposed on opposite ends of this body member 1 are rail flange-engaging means 2 and 3.

The rail flange-engaging means 3 is adapted 40 to engage the vertical edge of the rail base flange and it consists of a lip or upturned portion 4. The rail flange-engaging means dis-

posed on the other or opposite end of the body member comprises a clamping means 2. This 45 clamping means has an upper substantially rigid pressure-bearing member or jaw 5 which is designed to engage the upper surface of the rail base flange.

Preferably, the upper pressure-bearing member 5 is shaped similar to and conforms with the upper surface of the rail base flange which it is adapted to engage.

Connected to the upper bearing member and 50 disposed beneath it is another substantially

rigid pressure-bearing member or jaw 6. This pressure-bearing member 6 is spaced from and is smaller in size, that is, shorter in length than the upper bearing member 5 and is adapted to engage the bottom surface 60 of the rail base flange. Extending from the smaller bearing member 6 in a downward direction is an arm 7 which is bent substantially at right angles, forming another arm 8 and constituting a tie-abutting means. Imme- 65

diately following the tie-abutting means there is a portion curved or bent upwardly and inwardly and designated by the reference numeral 9. Adjacent this bend 9 the member is bent upwardly and downwardly forming a 70 bend or curved portion 10 spaced from the bend 9 at its intermediate portion and terminating by contacting with the bend 9 at 11. As is apparent from the drawings, the curved portions or bends 9 and 10 form an S-shaped 75 spring member which is integrally connected to the body member 1. The contacting of the bends 9 and 10 at 11 prevents the spring action from extending to the body member 1. The bend 10 is so formed that it has an apex 80

12 disposed adjacent but spaced apart from the bearing member 6 and extending inwardly and away from the edge of the rail in the same direction as the rigid bearing members. It is also disposed beneath the upper rigid 85 bearing member 5 and is adapted to engage the bottom surface of the rail base flange.

The apex 12 is furthermore disposed in a plane higher than the plane of the smaller bearing member 6 and the normal vertical distance between the apex 12 and the rigid bearing member 5 is less than the vertical distance through the rail base flange which it is intended to grip and hold. Due to the bends 9 and 10 the apex 12 is yielding and resilient and forms a yielding lower pressure member and together with the rigid bearing members or jaws 5 and 6 constitute a three pressure bearing clamp.

The rail anchor may be made by either forging or by stamping out. If it is desired to make the rigid portions of the rail anchor rugged and unyielding and to make the yielding portions more resilient, the bar or material from which the rail anchor is formed 100 may be rolled and progressively reduced in cross-section. If made in this manner the rigid bearing member 5 is made of a substantial thickness, the rigid bearing member 6 of a lesser thickness and the tie-abutting means 105 110

7 and 8, as well as the body member 1, are respectively made of lesser thickness. In other words, the rigid bearing member 5, the rigid bearing member 6 and the tie-abutting means 7 and 8, the bends 9 and 10 and the body member 1 may be made of different thickness or cross-section depending upon the resiliency or resistance desired in these various parts.

In application the anchor is applied to the rail base flange and is pushed on as far as it will go. At the end of this operation the rail anchor will assume a position with respect to the rail as illustrated in Figure 4. The anchor is then struck by means of a spike maul or sledge on the bend or shoulder-like portion 13 of the rigid bearing member 5.

Due to the force applied and the pressure exerted by the rail base flange to which the anchor is being applied, the resilient bearing member or apex 12 is depressed as clearly shown in Figure 5. This operation permits the rigid bearing members to pass on the rail base flange. This operation is continued until the lip 4 clears the opposite edge of the rail base flange and snaps into position. In applying the anchor the contact point 11 functions as a fulcrum or pivot and allows the free end of the body member to be sprung down until the lip 4 snaps into place.

When applied, the rail anchor exerts a pressure on the rail base flange through the triple pressure-bearing clamp comprising the upper rigid bearing member or jaw 5, the lower rigid bearing member or jaw 6 and the resilient bearing member 12. As a result of the depression of the resilient bearing member 12, the vertical edge-engaging means or lip 4 is moved upwardly and inwardly and, after application, it exerts a corresponding pressure on the rail base flange. If frozen in ballast, the vibratory movements of the rail and the pulling down on the heel 14 of the clamp will tend to throw the lip end and body member upward and effect a pulling in on the lip, thus increasing the grip on the rail edge and tearing the anchor out of the frozen ballast without any danger of pulling the lip end down and off the rail.

I claim:

1. A rail anchor comprising a body member, rail base flange-engaging means disposed at opposite ends thereof; one of said means comprising a clamp, said clamp comprising two pressure-bearing members and a yielding flexible pressure-bearing member disposed beneath one of said bearing members.

2. A rail anchor comprising a body member, rail base flange-engaging means disposed at opposite ends thereof, one of said means comprising a clamp having three pressure-bearing members, said members extending in the same direction.

3. A rail anchor comprising a body member, rail base flange-engaging means disposed at opposite ends thereof, one of said means

comprising a clamp, said clamp comprising two substantially rigid pressure-bearing members and a yielding flexible pressure-bearing member.

4. A rail anchor comprising a body member, rail base flange-engaging means disposed at opposite ends thereof, one of said means comprising a clamp, said clamp comprising two substantially rigid pressure-bearing members and a yielding flexible pressure-bearing member, said members extending in the same direction. 70 75

5. A rail anchor comprising a body member, rail base flange-engaging means disposed at opposite ends thereof, one of said means comprising a clamp, said clamp comprising an upper pressure-bearing member, a lower pressure-bearing member shorter in length than said upper member, and a resilient yielding pressure-bearing member cooperating 80 85 with said members constituting an element of said clamp.

6. A rail anchor comprising a body member, rail base flange-engaging means disposed at opposite ends thereof, one of said means comprising a clamp, said clamp comprising an upper pressure-bearing member, a lower pressure-bearing member shorter in length than said upper member, and a resilient yielding pressure-bearing member adapted to engage the bottom of the rail base flange 90 95 cooperating with said members and constituting an element of said clamp.

7. A rail anchor comprising a body member, rail base flange-engaging means disposed at opposite ends thereof, one of said means comprising a clamp, said clamp comprising an upper pressure-bearing member, a lower pressure-bearing member shorter in length than said upper member, and a resilient yielding pressure-bearing member spaced from 100 105 said members and constituting an element of said clamp.

8. A rail anchor comprising a body member, rail base flange-engaging means disposed at opposite ends thereof, one of said means comprising an upper pressure-bearing member, a lower pressure-bearing member shorter in length than said upper member, and a resilient yielding pressure-bearing member normally in a plane higher 110 than the plane of the lower member and cooperating with said members and constituting a triple pressure-bearing clamp.

9. A rail anchor comprising a body member, rail base flange-engaging means disposed at opposite ends thereof, one of said means comprising an upper pressure-bearing member, a lower pressure-bearing member shorter in length than said upper member, and a 120 resilient yielding pressure-bearing member normally in a plane higher than the plane of the lower member, said yielding member being disposed adjacent said lower member and spaced therefrom and cooperating with said 125 130

members and constituting a triple pressure-bearing clamp.

10. A rail anchor comprising a body member, means for engaging the vertical edge of a rail base flange disposed at one end of said body member, jaws adapted to engage the opposite rail base flange disposed at the other end of said body member, said jaws comprising an upper substantially rigid pressure-bearing member and a lower substantially rigid pressure-bearing member shorter in length than said upper member, an arm extending downwardly from said lower member bent substantially at right angles and forming tie abutting means, an inwardly and upwardly curved portion and a bend extending upwardly and outwardly from said portion and forming a yielding pressure member cooperating with said jaws to form a triple-pressure bearing clamp.

11. A rail anchor comprising a body member, means for engaging the vertical edge of a rail base flange disposed at one end of said body member, jaws adapted to engage the opposite rail base flange disposed at the other end of said body member, said jaws comprising an upper substantially rigid pressure-bearing member and a lower substantially rigid pressure-bearing member shorter in length than said upper member, an arm extending downwardly from said lower member bent substantially at right angles and forming tie abutting means, an inwardly and upwardly curved portion, and a bend extending upwardly and outwardly from said portion and forming a yielding pressure member cooperating with said jaws to form a triple-pressure bearing clamp, said bend terminating and contacting on said curved portion.

12. A rail anchor comprising a body member, rail flange-engaging means disposed at opposite ends thereof, one of said means comprising a clamp having two substantially rigid pressure-bearing members and a yielding pressure member comprising an S-shaped spring member, said spring member having its upper portion terminating and contacting with its middle portion or bend.

13. A rail anchor comprising a body member, rail flange-engaging means disposed at opposite ends thereof, one of said means comprising a clamp, said clamp comprising an upper pressure-bearing member, a lower pressure-bearing member and a resilient

yielding pressure-bearing member disposed adjacent said lower pressure-bearing member and beneath said upper pressure-bearing member.

14. A rail anchor comprising a body member, rail flange-engaging means disposed at opposite ends thereof, one of said means comprising a clamp, said clamp comprising two substantially rigid pressure-bearing members, a yielding flexible pressure-bearing member cooperating with said rigid pressure-bearing member and comprising an S-shaped spring member.

15. A rail anchor comprising a body member, rail flange-engaging means disposed at opposite ends thereof, one of said means comprising a clamp, said clamp comprising an upper pressure-bearing member, a lower pressure-bearing member shorter in length than said upper member, a resilient yielding pressure-bearing member disposed adjacent said lower pressure-bearing member and beneath said upper pressure-bearing member and comprising an S-shaped spring member.

16. A rail anchor comprising a body member, rail flange-engaging means disposed at opposite ends thereof, one of said means comprising a clamp, said clamp comprising two pressure-bearing members and a yielding flexible pressure-bearing member disposed beneath one of said pressure-bearing members and adjacent the other pressure-bearing member.

17. A rail anchor comprising a body member, rail flange-engaging means disposed at opposite ends thereof, one of said means comprising a clamp, said clamp comprising two substantially rigid pressure-bearing members and a yielding flexible pressure-bearing member disposed beneath one of said rigid pressure-bearing members.

18. A rail anchor comprising a body member, rail flange-engaging means disposed at opposite ends thereof, one of said means comprising a clamp, said clamp comprising two substantially rigid pressure-bearing members and a yielding flexible pressure-bearing member disposed beneath one of said rigid pressure-bearing members and adjacent the other rigid pressure-bearing member.

In testimony whereof, I have affixed my signature to this specification.

CHARLES B. SHEPHERD.
